JOSEPH W. WOHLHETTER, OF EAST ORANGE, NEW JERSEY, ASSIGNOR TO KEYSTONE STAMPING CORPORATION, A CORPORATION OF NEW JERSEY

MOPSTICK HEAD

Application filed March 25, 1931. Serial No. 525,066.

While this invention relates in general to mopstick heads it relates more particularly to that type having substantially inverted T-shaped gripping jaws extending transversely 5 to the handle stick, and the shank or stem of one of which is pivotally connected to the shank or stem of the other for transverse gripping and releasing movements. Commonly these jaws are pressed into gripping 10 relation by means of some sort of positively acting screw clamping device which also may be operated to release the jaws. Commonly also only one of these jaws is movable, the other jaw having a fixed relation to the handle stick of the mop, so that when a mop is gripped between these jaws it is out of center line with the handle stick, thereby obviously rendering the use of the mopstick more or less 15 inconvenient, as well as less effective.

Among the objects of this invention are to provide an improved mopstick which may be conveniently and quickly operated for gripping or releasing the mop and which will be convenient and effective in use for mopping 20 purposes. More general objects of the invention are to provide a mop head construction which is light, strong, durable, of few parts, and of which the major parts may be conveniently and inexpensively stamped and 25 formed from suitable sheet metal. Other and more particular objects and advantages of the invention will hereinafter appear.

In carrying out the invention, a pair of gripping jaws which are pivoted together are 30 operated in their gripping action through the intermediary of a spring which is interposed in the operating connections. Also each of such jaws is separately pivotally mounted on a head member by which both of the jaws are 35 carried, this head member being firmly and rigidly secured on the lower end portion of the handle stick. As a further feature of the invention, the pivotally connected stems or shanks of the T-shaped gripping jaws have a 40 relatively longitudinally sliding cam engagement with a cooperating cam element whereby these jaws may be either opened or closed by relative movement between the pivots of the jaws and such cam element. More particularly, such cam element is rigidly and

stationarily supported relatively to the above noted head member and may conveniently be formed in the same piece therewith, while the pivotal connection between the jaws has sliding movement longitudinally of such head 55 member and the handle stick to which it is secured. The invention further includes various features of construction and combinations of parts, as will appear from the following description.

One embodiment of the invention, shown in the accompanying drawing, will now be particularly described and thereafter the invention will be pointed out in claims, reference now being had to the drawing, in which:

Fig. 1 is a side elevation of a mopstick head construction embodying the invention, secured on the lower end portion of a handle stick and showing the gripping jaws as closed, but with the mop itself omitted;

Fig. 2 is a reduced inverted plan view of Fig. 1;

Fig. 3 is a front elevation as viewed from the right in Fig. 1;

Fig. 4 is a similar view in partial central 75 vertical section on the line 4-4 of Fig. 1; and

Fig. 5 is a view similar to Fig. 1 but with the gripping jaws open and is in other respects a central vertical section on the line 80 5-5 of Fig. 3.

The embodiment of the invention shown in the drawing will now be particularly described with reference to such drawing. The lower end portion of a handle stick 1 is shown 85 as flattened on one side as at 2, and this lower end portion may be slightly tapering if so desired. This end portion of the stick 1 snugly fits within a rather long ferrule socket 3 having a flattened side wall 4 which cooperates 90 with the flattened side 2 of the handle stick to prevent rotation of the latter in the ferrule 3, as well as also serving a further purpose, as will hereinafter appear. In the embodiment of the invention shown in the drawing, 95 the ferrule 3 constitutes the inner or upper portion of a one-piece head member which further includes an outwardly or downwardly projecting open receptacle socket of substantially rectangular cross section and 100

which comprises a pair of similar opposite flat parallel side walls 5 and a pair of opposed diverging or flaring guide walls 6 having edge portions 7 curved outwardly thereby to 5 provide cam members having inner rounded cam surfaces. This one-piece head member, comprising the above noted portions 3 to 7 inclusive, may be stamped and shaped from suitably heavy and strong sheet metal with 10 a longitudinal joint or seam 8 between the edges of the shaped blank along the back of such head member, as indicated in Figs. 4 and 5. If desired, for the sake of increased strength in the rear flaring wall 6, of course 15 the adjacent edges of the sheet metal along this seam 8 may be soldered or otherwise secured together, as indicated in Fig. 5.

It will be noted from the drawing that the parallel walls 5 are spaced a greater distance 20 from one another than the diameter of the ferrule 3, so as thereby to form outer shoulders 9 at the points of junction and merging together of these walls 5 and the flaring walls 6, with the circular portions of the walls of 25 the ferrule 3. It may be noted also in this connection that the flat wall 4 of this ferrule 3 is at the front, adjacent the front flaring wall 6. Half way between the above noted cam members 7 and in a plane which is coincident with the axes of the handle stick 1 and ferrule 3, the edges of the respective parallel walls 5 have inturned projections or lugs 10 which constitute cam members and the lateral edges of which form cam guides. The purpose 30 of these cam members 7 and 10 will be presently described. At a middle point of their width and also in the above noted axial plane, the parallel walls 5 have through them rather long straight longitudinal slots 11, the purpose 35 of which will also presently appear.

In further carrying out the invention in accordance with the embodiment thereof shown in the drawing, a pair of substantially similar generally T-shaped mop-gripping 40 members or gripping jaws 12, having stems or shanks 13 formed in the same piece therewith, are provided. These gripping members or jaws 12, as a whole, to include their stems 13, may each be desirably stamped and shaped 45 from suitable heavy and strong sheet metal, so as to have a minimum of weight together with a maximum of strength. The T-heads 12 extend transversely in parallel relation with one another and are movable to and from 50 one another for releasably gripping and holding a mop (not shown) between them. Each of these mop-gripping heads 12 is shown as of nearly semi-circular arcuate shape in cross section and as tapering outwardly from 55 its stem 13, which latter is shown as of a substantially rectangular rather shallow trough shape in cross section, with the web portion of said trough slightly longitudinally concavely curved, while the flanges of this web 60 are slightly convexly curved along their

edges, with a gradual taper towards the end of the stem 13, as clearly shown in the drawing. The outer or lower mop-gripping edges of the T-heads 12 may be desirably provided with relatively interfitting undulations, as 70 shown at 14 in Fig. 2, for thereby more securely holding the gripped mop between them, or these gripping edges may be otherwise shaped for effectively serving this purpose. 75

The trough-shaped or substantially U-shaped stems or shanks 13 of the gripping jaw members extend upwardly into the above described projecting receptacle or socket, with their flanges at their inner ends disposed in overlapping relation with one another for the respective stems 13 and there pivotally connected together. The shape or contour of these stems 13 are such that their web portions form cam members which have a sliding cooperating engagement with the cams formed by the outwardly curved cam edges 7 of the flaring walls 6, while the adjacent inner edges of the flanges of these stems 13 form sliding cam members which have a co-operating engagement with the inturned cam lugs 10 on the edges of the parallel walls 5, as clearly shown in the drawing, particularly 80 in Figs. 1 and 5.

The inner or upper ends of the stems 13 95 of the gripping jaws 12 are pivoted together by means of pivot pins or journals 15 passing through their overlapping flanges and extending out through the guide slots 11, to the outer sides of the flat parallel walls 5, being 100 slidably guided for longitudinal movement along these slots 11 almost but not quite throughout the length of these longitudinal slots, as clearly indicated in the drawing in Figs. 1, 3 and 4 for the inner or upper position, and in Fig. 5 for the lower or outer position. The pivot pins 15 have inner turned-over end portions 16 for preventing their escape outwardly. At the outer sides of the walls 5 these pivot pins 15 have substantially 110 similar turned-over portions 17 which are continued as extensions to form a pair of substantially upwardly extending operating links. The upper end portions of these links 17 are rebent inwardly in the form of hooks 18. These hook ends 18 of the links 17 are pivotally connected to the projecting side edge portions of a longitudinally curved sheet metal handle lever 19 of substantially usual form. 115

The inner end of this handle lever 19 is shown as provided with an eye 20 by means of which it is pivotally connected to the upper terminal convolution of a substantially usual coiled compression spring or thrust spring 21 which surrounds the ferrule socket 3 and the other or lower end of which abuts against the above noted outer shoulders 9. In the construction shown in the drawing, idle upward shifting movement of this spring 120 125 130

21 is prevented and also at the same time the ferrule 3 of the above described head member is further secured on the handle stick 1, by means of a staple 22 which engages over the lowermost convolution of the spring 21 and passes through the wall of the ferrule 3 into the handle stick 1 adjacent to its lower end. However, it is obvious that various other substantially different devices could be utilized for serving either one or the other or both of these purposes. It may be noted that the flattened side wall 4 of the ferrule 3 provides a desirable free space as well as also a bearing surface for the pivot eye 20 of the handle lever 19 on the coil of the spring 21.

It is believed that the manner of operation and advantages of the invention should be clearly evident from the preceding description taken in connection with the drawing, but may be briefly epitomized. A powerful compressive gripping action will be brought to bear by the gripping jaws 12 upon the interposed mop by reason of the combined pivotal and cam arrangement. When a mop is gripped by these jaws, such gripping jaws will then of course be held more or less apart, depending upon the thickness of the material of the mop. In such case, the slideable pivots 15 of the jaw members 12 will be stopped by the gripped mop at a lower point along the guide slots 11 than is shown in Fig. 1, for example, and since the handle lever 19 is a floating lever interposed between and pivotally connected to the operating links 17 and to the spring 21, this handle lever will then be stopped by the links 17 at a lower position than that shown in Figs. 1 and 3, by reason of the yielding of the spring 21, which will then be further compressed. In any case this compressed spring 21, in cooperation with the cam members 7 and 13, will hold the gripping jaws 12 in secure gripping relation with the interposed mop, regardless of whether the latter is thicker or thinner, and accordingly holds these jaws apart to a greater or a less extent.

During the first or initial part of movement of the handle lever 19 away from its locked position, as shown in Figs. 1 and 3, the spring 21 will be relieved of its compression, and thereafter, with continued outward and downward movement of this handle lever 19, the operating links 17 will move their pivots 15 outward or downward along the guide slots 11, in which the pivot pins 15 are also pivoted as well as slideable, thereby causing the above described cooperating cam members to spread the gripping jaws 12 a considerable distance apart from one another, as is shown in Fig. 5, since the spring 21 is prevented from upward movement as a whole by the staple 22. In view of the fact that both of the gripping jaws 12 are equally pivotally moved relatively to the head member which

includes the ferrule 3, these jaws will at all times and in any position thereof be symmetrically disposed and at equal distances from the center line or axes of the handle stick 1 and ferrule 3 of the head member 70 upon which these gripping jaws are mounted.

Among various modifications in construction which might be made while still more or less effectively carrying out the idea of the invention in accordance with the principle thereof, it might be noted that the inner ends of the stems 13 of the gripping jaws 12 might be deprived of their sliding movement and stationarily pivoted, for example by means of their pivot pins such as 80 15, directly on the adjacent end portion of the ferrule 3. In such case the cam-carrying receptacle or socket having the cams 7 and 10 could be made as a separate piece from the ferrule 3 and mounted to slide longitudinally thereon with the inner or lower end of the gripping spring 21 abutting against shoulders such as 9, for then moving these cams outward instead of moving the pivots 15 and gripping jaws inward, as shown in the drawing. Also it should be obvious from the drawing that instead of the two separate pivot pins 15, a single pivot pin or the like could extend all of the way across from one side to the other, through the overlapping flanges of the gripping jaw stems 13 at both sides and out through both slots 11 in the walls 5 of the cam socket, and in fact such a construction in this respect is shown in my later copending application Serial No. 100 573,060, filed November 5, 1931, for mop-stick heads. In fact, various modifications may be made in the construction shown in the drawing and above particularly described, within the principle and scope of the invention as defined in the appended claims.

I claim:

1. In a mopstick head construction, the combination of a head member having a securing portion by which it may be attached to a handle stick and having a projecting terminal socket portion of substantially rectangular cross section, said socket portion having two parallel walls and two outwardly flaring walls, each of said parallel walls being provided with a longitudinal slot, a pair of T-shaped mop-gripping members the T-heads of which form parallel gripping jaws and the stems of which extend into said socket portion respectively adjacent to its flaring walls, pivot means connecting the inner ends of said stems and slideable in said slots, the edge portions of said flaring walls and the adjacent outer sides of said stems forming cooperating cam elements which draw said gripping jaws together when said pivot means is retracted along said slots, a spring acting to retract said pivot means along the said slots for causing said jaws to grip the mop, and manually operable means for re-

leasing said spring and for thereafter moving said pivot means outwardly along said slots for thereby permitting said gripping jaws to open.

- 5 2. In a mopstick head construction, the combination of a head member having a securing portion by which it may be attached to a handle stick and having a projecting terminal socket portion of substantially rectangular cross section, said socket portion having two parallel walls and two outwardly flaring walls, each of said parallel walls being provided with a longitudinal slot, a pair of T-shaped mop-gripping members the 10 T-heads of which form parallel gripping jaws and the stems of which extend into said socket portion respectively adjacent to its flaring walls, pivot means connecting the inner ends of said stems and slidably in said 15 slots, the edge portions of said flaring walls and the adjacent outer sides of said stems forming cooperating cam elements which draw said gripping jaws together when said pivot means is retracted along said slots, a 20 cam guide on said socket portion to cooperate with the adjacent inner sides of said stems for spreading said gripping jaws when said pivot means is moved outwardly along said slots, a spring acting to retract said pivot 25 means along the said slots for causing said jaws to grip the mop, and manually operable means for releasing said spring and for thereafter moving said pivot means outwardly along said slots for thereby opening said 30 gripping jaws.

3. In a mopstick head construction, the combination of a head member having a securing portion by which it may be attached to a handle stick, a projecting terminal socket 40 mounted on said member of substantially rectangular cross section having two parallel walls and two outwardly flaring walls, a pair of T-shaped mop-gripping members the stems of which extend into the said socket 45 respectively adjacent to its flaring walls, pivot means connecting together the inner ends of the said stems, the said pivot means and socket being mounted for relative sliding movement longitudinally of the socket, the edge portion of said flaring walls and the adjacent outer sides of said stems forming 50 cooperating cam elements which draw said gripping members together when the direction of the said relative sliding movement is such that the said stems enter into the said socket, a cam guide on said socket to cooperate with the adjacent inner sides of said stems for spreading said gripping members when the direction of the said relative sliding movement is such as to move the said stems out of the said socket, a spring acting to produce said relative sliding movement in the direction for causing said gripping members to grip the mop, and manually operable means for releasing said spring and for 55 60 65 70 75 80 85 90 95 100 105 110 115 120 125 130

thereafter imparting said relative sliding movement in the direction for opening said gripping members to release the mop.

4. In a mopstick head construction, the combination of a head member having a securing portion by which it may be attached to a handle stick, a projecting terminal socket of substantially rectangular cross section having two parallel walls and two outwardly flaring walls, a pair of T-shaped mop-gripping members the stems of which extend into said socket respectively adjacent to its flaring walls, pivot means connecting together the inner ends of said stems, the said pivot means and the said socket being mounted for relative sliding movement in a direction longitudinal of the socket, the edge portions of said flaring walls and the adjacent outer sides of said stems forming cooperating cam elements which draw said gripping members together upon relative sliding movement of said pivot means and said socket in a direction to cause the said stems to enter into the socket, and manually operable operating means interposed between the said socket and the said pivot means for producing the said relative sliding movement in each direction thereof.

5. A mopstick head comprising a member including a handle-receiving section and a socket section adapted to cooperate with a pair of gripping jaws, the wall of the socket section having a pair of opposed elongated slots therethrough for a jaw operating element, a spring surrounding the handle-receiving section of the member, a lever pivoted on the spring, a jaw-operating element pivotally secured to the lever and extending through the slots in the wall of the socket section, and a pair of opposed gripping jaws having stems extending into and being slidably mounted in the socket section, the said jaw stems being pivotally secured to the jaw-operating element and the distance between the jaw stems when withdrawn into the socket being such that the stems bear against the wall of the socket in the closed position of the jaws.

In witness whereof, I hereunto subscribe my signature.

JOSEPH W. WOHLHIEDER.
